[57] **CLAIM**

The ornamental design for a two-wheel frame, as shown and described.

DESCRIPTION

FIG. 1 is a top, rear and left side perspective view of a two-wheel frame, showing my new design;
FIG. 2 is a right side view thereof;
FIG. 3 is a left side view thereof;
FIG. 4 is a front view thereof;
FIG. 5 is a rear view thereof; and,
FIG. 6 is a top plan view thereof.
The broken line showing of the bicycle seat, handle, tires, sprocket wheel and pedals in FIG. 2 is for illustrative purposes only and forms no part of the claimed design.

FIG. 1

FIG. 2

FIG. 3

FIG. 5

FIG. 6

FIG. 4
